UNITED STATES PATENT OFFICE.

HENRY D. POWNALL, OF CANTON, OHIO.

SCORED ICE BLOCK AND METHOD.

Application filed February 6, 1923. Serial No. 617,279.

To all whom it may concern:

Be it known that I, HENRY D. POWNALL, a citizen of the United States, residing at Canton, in the county of Stark and State 5 of Ohio, have invented certain new and useful Improvements in Scored Ice Blocks and Methods, of which the following is a specification.

My invention relates to improvements in 10 scored ice blocks and method of production thereof. One of its objects is to provide as an improved article of manufacture ice blocks, preferably blocks of artificial ice, scored in special manner to enable the 15 ice to be transported in large units to the locality of consumption, and to then be readily subdivided along scored lines into smaller units, respectively of uniform weight. Another object is to provide as an improved 20 article of manufacture ice blocks, scored in special manner to enable the ice to be transported in large units without liability of accidental division into smaller units, and at the same time adapted to have smaller 25 units respectively of substantially uniform weight and symmetrical outline successively detached from such larger unit as required for delivery or consumption. Another object is to provide as an article of manufacture 30 ice blocks each having a special system of score lines whereby the whole blocks or large units are well and firmly held together for the purpose of transportation as large units, and not liable to be accidentally 35 separated into smaller units in transportation, and which are readily separable by the use of a suitable tool into units of smaller dimensions and symmetrical outline at the place or places of delivery. Another object 40 is to provide an improved method or art of scoring ice blocks. My invention also comprises certain details of form, order of procedure, and combination of components, all of which will be fully set forth 45 in the description of the accompanying drawings in which:

Fig. 1, is a side elevation of a block of artificial ice embodying my improvements.

Fig. 2, is an enlarged sectional detail 50 taken on line 2—2 of Fig. 1.

Fig. 3, is a perspective view of a small unit or fraction separated from the larger unit shown in Fig. 1.

My invention is adapted to be applied to 55 large units of natural ice, and to large units of artificial plate ice, and is especially de-

signed for and applicable to the large blocks or units of artificial can ice more generally produced. It is designed to enable the large ice blocks or units to be conveniently and economically scored by apparatus located at the ice house or factory, in quantity, and in such manner that the ice may be handled and transported in the form of large units to its destination or point of consumption, 60 and there readily divided uniformly along said score lines into smaller units of substantially uniform weight and symmetrical outline.

Heretofore it has been difficult for honest- 70 ly disposed ice delivery men to divide the larger blocks of ice into smaller units of substantially uniform weight and symmetrical outline. The smaller blocks of irregular outline have imperfectly fitted the 75 ice compartments of the respective ice boxes of the consumers, and the irregularity in the weight of the units delivered from day to day, has caused dissatisfaction on the part of consumers. Also dishonestly dis- 80 posed ice delivery men have, for their own interests, purposely so divided the large blocks of ice into smaller units as to intentionally deliver short weight pieces of ice to regular consumers in order that they might 85 thus provide a supply of ice to be sold to transient customers and the proceeds of such sales to transients appropriated by the ice delivery men to their own use to the mutual injury and dissatisfaction of the ice dealer 90 and his regular customers.

The accompanying drawings illustrate the preferred embodiment of my invention in which 16 represents a large size block of ice as for instance a three or four hundred 95 pound block of artificial ice such as is ordinarily manufactured in, and released from, artificial ice cans of standard dimensions. The block 16 is usually tapered on its four sides from one end to the other 100 sufficiently to enable the ice blocks to be readily withdrawn from the ice cans as soon as the ice has been loosened from the walls of the ice cans. A core 17 of more or less porous or spongy ice is ordinarily 105 formed through the center of the ice block from end to end thereof, while the ice surrounding said core is dense strong and transparent.

Score lines 18 and 19 preferably of uniform depth are cut or formed from end to end of the large blocks 16 by any serviceable

means, as for instance by means of saw cuts. A series of substantially parallel score lines 20 and 21, of greater depth at their centers than at their ends are formed transversely to the score lines 18 and 19, upon opposite sides of the large ice block 16, as for instance by means of circular saw cuts. The large ice blocks 16 are thereby partially severed by the score lines or cut 18 and 19 and 20 and 21 into a series of smaller sections or ice blocks 24, which are substantially rectangular in outline and of nearly the same dimensions, and by spacing the score lines 20 and 21 the proper relative distances apart, the several smaller sections or blocks 24 may be so proportioned as to be all of substantially the same weight, notwithstanding the tapered form of the large block 16.

It will be noted from Fig. 2, that the un-scored or unsevered portion 26 of the large ice block is in cross section substantially the same as that of an I-beam, and that the unsevered portion is chiefly located at both ends of the I-beam where strength is most required and is chiefly of solid ice of maximum strength, hence the large ice block is of a cross sectional pattern calculated to prevent premature or accidental separation of the large block into fractions, while the application of an ice pick or axe as a wedge along one or more of the scored lines will cause a cleavage, controlled by and uniformly in plane with the scored lines to thereby produce small ice blocks of substantially uniform outline and proportion and of uniform weight. In practice the application of an ice pick or similar instrument at the point and in substantially the direction indicated by the arrow 30 in Fig. 2, from one side only of the large ice blocks will be sufficient to initiate a cleavage along and in plane with one of the score lines 20 or 21. A subsequent similar application of an ice pick along a short section of one of the score lines 18 or 19 will serve to separate two small ice blocks 24 one from the other along a line of cleavage in plane with the score lines 18 and 19.

Where my improved score lines are applied to natural ice or to plate ice, the score lines 20 and 21 may be spaced uniform distances apart to produce small ice blocks of uniform weight. Where the score lines are applied to tapered ice blocks taken from ice cans, the score lines 20 and 21 are unevenly spaced apart as indicated in Fig. 1, in order that the respective small blocks may be of uniform weight but of slightly different dimensions. In the natural ice, the plate ice, and the can ice, the score lines and the lines or planes of cleavage in the unsevered portions of the ice are caused to act in harmony to produce small ice blocks of symmetrical outline and uniform weight.

The article herein shown and described is

capable of considerable modification without departing from the spirit of my invention.

What I claim is:—

1. An improved article of manufacture 70 comprising a large ice block having opposed score lines longitudinally thereof and a plurality of score lines of greater depth at their centers than at their ends intersecting said longitudinal score lines at substantially 75 right angles thereto and spaced apart to insure division of said large ice block into a series of smaller ice blocks of substantially uniform weight.

2. An improved article of manufacture 80 comprising a large ice block having a series of score lines in one side thereof of greater depth at their centers than at their ends, said score lines being substantially parallel and spaced apart to enable said ice to be 85 transported as a large unit and to insure division of said large ice block by fracture into a series of smaller ice blocks of substantially uniform weight.

3. An improved article of manufacture 90 comprising a large ice block having a series of opposed score lines in opposite faces thereof each of greater depth at its center than at its ends and terminating at opposite ends near the limits of the face in which it is cut, said score lines being substantially parallel and spaced apart to enable said ice to be transported as large units and to insure division of said large ice block into a 95 series of smaller ice blocks of symmetrical 100 outline and uniform weight.

4. An improved article of manufacture comprising a large ice block having a pair of opposed score lines longitudinally thereof and a series of opposed score lines transversely of said longitudinal score lines in opposite faces of said ice block, each of said transverse score lines being of greater depth at its center than at 105 its ends and terminating at opposite ends near the limits of the face in which it is cut, said transverse score lines being substantially parallel and spaced apart to enable said ice to be transported as a large unit 110 and to insure division of said large ice block into a series of smaller ice blocks of symmetrical 115 outline and uniform weight.

5. The method of subdividing large ice blocks into a series of smaller ice blocks of 120 symmetrical outline and uniform weight which comprises scoring opposite faces of large ice blocks at the ice factory with a series of parallel score lines spaced apart in pairs and each score line of greater depth 125 at its center than at its ends leaving a continuous connecting I-beam shaped connecting core, and subsequently causing a cleavage of the ice controlled by and in plane with said score lines to subdivide said large 130 ice blocks into a plurality of smaller ice 135 blocks.

blocks of symmetrical outline and uniform weight.

6. The method of subdividing large ice blocks into a series of smaller ice blocks of symmetrical outline and uniform weight which comprises first scoring one face of each large ice block with a series of parallel score lines spaced apart, and each of greater depth at its center than at its ends thereby leaving a continuous connecting core from end to end of said large ice block thicker at opposite sides than at its center, transporting said large scored ice blocks and subsequently after transportation dividing said large ice blocks by fracture into a plurality of small ice blocks of symmetrical outline and uniform weight.

7. An improved article of manufacture

comprising a large ice block having a series of score lines in one face thereof and an unsevered core extending from end to end of said large ice block, said score lines being substantially parallel and spaced apart and of greater depth at their centers than at their ends, and said unsevered core being thicker and stronger at opposite sides than at its center, to thereby enable said large scored ice block to be transported as a unit and to be divided by fracture after transportation into a plurality of smaller ice blocks of symmetrical outline and uniform weight.

In testimony whereof I have affixed my signature.

HENRY D. POWNALL.
